UNITED STATES PATENT OFFICE.

LADISLAUS KURPIEL, OF PRAGUE, CZECHOSLOVAKIA.

BOX OPENER.

Application filed February 17, 1927, Serial No. 169,026, and in Czechoslovakia March 10, 1926.

This invention relates to a box opener and consists essentially in a plate or disc rotatably supported on the box and engaging with its edge between the rim of the box and the rim 5 of the lid, the plate being provided with pressed out eccentric ribs, which bear against the edge of the lid when the plate is rotated, and thereby raise the lid.

In the accompanying drawings one constructional example of the box opener is illustrated,

Figure 1 being a front elevation thereof,

Figure 2 a plan, and

Figure 3 a side elevation.

The box 1 is closed in the usual manner by a slip-on lid 2. On a pin 3 on the box 1 is rotatably mounted a plate 4, on the edge of which projecting teeth 5 are arranged, which are suitably bent back so as to lie in recesses 7 in the cylindrical surface of the box 1. When the box is closed the teeth are located under the edge of the lid 2, so that as the plate 4 is rotated, the latter moves between the rims 20 of the box and the lid.

The circumferential bead 6 on the box limiting the slipping-on of the lid is interrupted in the neighbourhood of the plate.

On each side of the pivot 3 is pressed out of the plate 4 an eccentric rib 8, which slides on the edge of the rim of the lid, when the plate 4 is rotated. By this means the lid is raised.

What I claim is:—

A box opener comprising a plate rotatably mounted upon the neck of a box, eccentric ribs pressed out of the said plate and leaving narrow projecting edges of the plate, these latter edges terminating in tooth-like points bent backwards, and recesses provided near the reach of the seam of the box for the reception of the backwardly-bent tooth-like points, as and for the purpose set forth.

In testimony whereof I have signed my name to this specification.

LADISLAUS KURPIEL.
